SUPPORT FOR CURTAINS, DRAPERIES,
AND THE LIKE

Louis Abrams, Springfield, Mass.

Application November 7, 1947, Serial No. 784,579

1 Claim. (Cl. 160—348)

1

This invention relates to a support for holding curtains, draperies, and the like in pleated form and has for an object to provide an improved device of this character into which a drapery may be readily and easily assembled, said support positively holding the pleated form of the drapery against chance disarrangement.

Another object is to provide a support of this type assuring a pleasing and attractive appearance in hanging a drapery in symmetrical folds and for doing this without excessive handling of the material to achieve the desired ornamental effect.

A further object is to provide a support which may be hung at each upper corner of a window or door frame or which may be used as a tieback.

These and other objects and advantages of my invention will be apparent from the following description of an embodiment of the same in connection with the accompanying drawings in which,

Fig. 1 is a perspective view of the support;

Fig. 2 is a sectional view on line 2—2 of Fig. 1;

Fig. 3 is a plan view of the back side of the support;

Fig. 4 is a view on line 4—4 of Fig. 3 to show details of a latch mechanism for locking the device in compressed position;

Fig. 5 is a fragmentary view of a drape on a support fixed at the upper corner of a window or door frame;

Fig. 6 is a plan view of a flat blank from which the support may be formed; and

Fig. 7 is a plan view of the blank of Fig. 6 to show steps in the formation of the support.

In Fig. 1 the body of the support is shown as a series of folded portions 1 formed as a corrugated sheet 2 of resilient material, preferably springy sheet metal. The sheet 2 is shown in the form of a trapezoid, although the shape may be that of a triangle or square as desired.

Fixed for pivotal swinging movement with respect to sheet 2 at the upper edge 3 thereof, as seen in Fig. 2, are two retaining straps 4 having folds 5 therein and adapted to swing into and out of nested position with relation to the corresponding folds 1 of sheet 2.

It will be noted by reference to Fig. 5 that the drapery material 6 is placed in the folds 1 of the corrugated sheet 2, the edge of the cloth lying along the edge 3 of said sheet, and the straps 4 clamped in nested position to hold the drapery material pleated as shown. Thus a curtain or drapery may be hung to frame a window or doorway in a pleated arrangement with no effort on

2

the part of the decorator to obtain even folds. If desired the support may be shifted clockwise or counterclockwise from the position shown to achieve various pleated effects as may be readily appreciated.

In the particular embodiment of my invention as shown in the drawings, means for hanging the support from the upper left hand corner of a window frame is shown in Figs. 1 and 3. A looped wire bracket 8 is held in a folded portion of the straps 4 at the free ends thereof which are here shown as joined together. As shown (Fig. 1), the adjacent edge of one free end portion of a strap 4 overlaps the free end portion of the other strap. The outer ends thereof are turned under and the overlapping portions may be pressed to hold by frictional engagement. As shown at each outside edge of the turned portions, offsets are provided to form a beaded fold which receives the stem of the bracket 8. The loop 8' of the bracket is offset from the end of the corrugated sheet 2 and is adapted to lie against the inner edge of the vertical frame 9 (Fig. 5) of a window. At the diagonally opposite upper corner of the support a loop 10' of a wire bracket 10 is adapted to rest on the upper edge of the horizontal frame member 11 of the window (Fig. 5). The wire 10 is anchored in two mounting ears 12 and 13 struck from the metal of the uppermost fold 1 (Figs. 2 and 3). The brackets 8 and 10 may be adjusted to permit the support to hang from the window frame or, if desired, the same may be fixed to the frame by screws applied through the looped portions. It will be obvious that a similar support for the right hand corner of the frame will have similar brackets oppositely placed to provide a symmetrical appearance.

In the preferred form of drapery support I have found it desirable to provide means for holding the folds compressed when the drapery or other material is inserted therein, although I have found the resilient force of springy metal is in itself sufficient to hold the drapery by reason of friction and spring action of the straps in the nested position. As best seen in Figs. 2, 3, and 4, latch mechanism is provided at the rear of the support for holding the folds compressed in close relation. Two spaced fingers 15 and 16 of a plate 14 (attached by ears 17 projecting through the metal adjacent an outer fold 1 of the corrugated sheet), are bent to lie across the rear folds and project through a slot 19 cut in a central portion of a fold 1'. This fold 1' is enlarged at the rear for this purpose (Fig. 2).

An oppositely placed finger 20 adapted to slide between fingers 15 and 16 is similarly attached to an oppositely located outer fold by ears 21 and also projects through slot 19.

As seen at 22 (Fig. 3) each end edge of fold 1' is cut to form latch bar retaining ears 23 (Fig. 4). Ears 23 are bent to hold a latch bar 24 therebetween and longitudinally across slot 19 in the path of fingers 15, 16, and 20. The fingers 15 and 16 are provided with knuckles 26, finger 20 with knuckle 27, to receive the bar 24 when all of said knuckles are in alignment. In operation, the corrugated sheet 2 with the drapery inserted is compressed manually to align said knuckles 26 and 27 and the support is held so that bar 24 will drop by gravity into said knuckles. Release of manual pressure will cause the resiliency of the metal support to hold the bar in the knuckles due to the opposing pressures on the bar from the oppositely pulled fingers. The latch can be released by holding the support compressed and turning it to permit the bar to drop free of the knuckles.

In Fig. 6 is shown in greatly reduced scale a flat blank of resilient sheet metal from which the preferred form of my invention is made. The central portion 30 between the scored lines 31 is designed to form the sheet 2 of Fig. 1. The side strips 32 are designed to form the straps 4. The metal is cut along the lines 31 and nicked at the top thereof as at indentations 33. In the forming operation the body of the blank and the strips are stamped to shape the corrugations. The strips 32 are then turned over on the portion 30 and bent upwardly as at 35 in the manner illustrated by Fig. 7. The upper edge of portion 30 is preferably rolled to provide the edge 3 as shown in Fig. 2 with a strap 4 being adapted for swinging movement about edge 3 as an axis. The swinging movement is, of course, resisted by the resilient character of the metal or other springy material of which the support may be made.

It will be appreciated, as I have mentioned before, that the particular shape of the support may be modified according to the particular arrangement of curtain or drapery hanging desired. In the embodiment shown in the drawings the shape of the device may be that of any geometrical form, a circle, square, rectangle, etc. It will also be appreciated that the flat blank may be creased with groups of folds spaced from each other in-

stead of a continuous series of folds throughout.

The example of Fig. 5 showing a "festoon" arrangement will readily suggest the arrangement of a full drape framing the window. Also the device can be adapted for the hanging of straight drapes or be used as a tieback for the same. And, as before noted, the support can be fitted with attachment or hanging fixtures for positioning the same in any way desired.

Having described my invention, I claim:

In a device for supporting curtains, draperies and the like, an adjustable holder comprising a thin sheet of resilient spring metal having a series of corrugations arranged transversely of said sheet and having angular outwardly divergent flat sides, a strap overlying said sheet and provided with a series of mating corrugations lying in removably nested relation within the flat sided corrugations of said sheet, said strap being a continuation of said resilient sheet and integrally joined therewith at one end for pivoting of said strap at said end into end out of said nested relation, releasable means fixed on said sheet at the underside thereof for holding the corrugations in compressed relation, said means including a finger plate extending longitudinally under said sheet transversely of said corrugations and anchored to the sheet at one end thereof, said finger plate including laterally spaced side members, a second finger plate extending longitudinally of said sheet and anchored to the sheet at the opposite end thereof, said second plate lying between the side members of the first plate and in telescopic slidible relation therewith, and interlocking means to prevent relative longitudinal movement between the plates for an adjustable compressed relation of said nested strap and sheet.
